ABSTRACT OF THE DISCLOSURE

The device comprises a nozzle having a delivery orifice for the outflow of the fluid product, and a hollow valve slideable in the delivery orifice for closing it, this hollow valve including, at its outer end, a wall provided with a hole. Means are disposed in said hollow valve adapted to co-operate with said hollow valve during closing sliding of the hollow valve whereby said closing sliding of the hollow valve generates a suction inside said hollow valve, this suction being exerted through said hole and the drop of the product formed at the end of the delivery thereof on the outer side of said end wall.

The present invention relates to devices for feeding, for instance into packing containers, predetermined doses of a fluid product, in particular a liquid or pasty product (milk, yogurt, yogurt containing bits of fruits, or the like).

The chief object of the present invention is to provide a feeding device of this kind which is well adapted to meet the requirements of practice.

According to an essential feature of our invention, the feeding device is provided with means for collecting by suction the drops of product that tend to form when the valve through which the product is delivered is closed.

Other features of our invention will result from the following description of a preferred embodiment thereof hereinafter described with reference to the appended drawings and in which:

FIG. 1 is a diagrammatical view of a feeding device of the kind with which the present invention is concerned;

FIG. 2 is an axial section half view of an embodiment of the device according to the present invention, this device being shown in one position; and

FIG. 3 is a view similar to FIG. 2 showing the device in a different position.

The device with which the present invention is concerned belongs to an apparatus of the type illustrated by FIG. 1.

This apparatus includes an inlet pipe 9 for the product to be distributed, the feed of this product being controlled by a valve 10 consisting of a sheet of a resilient material limiting two chambers, respectively 14 located in frame 50 and which communicates with pipe 9 through a conduit 12, and 15 located in frame 22 and which communicates with a pipe 16 for the feed of compressed air. The liquid from pipe 9 flows into a main conduit 11 from which it passes through conduits 13 into respective cylinders 3 in which pistons 4 are slideable. From said cylinders 3 the product is fed to nozzles 25 from which it is delivered into suitable containers passing under said nozzles.

FIGS. 2 and 3 show a distributing nozzle made according to the present invention.

According to this embodiment of our invention, every nozzle is actuated by compressed air fed through a pipe 21, whereas the product to be distributed arrives through pipe 26, provided in frame 50.

5 The device comprises a valve 51 adapted to close the outlet 52, of relatively large cross section, of a distributing nozzle 25. Said valve 51 is hollow and cooperates with an axial guide 54 mounted in fixed position (possibly adjustable). The end wall 69 of said valve 51 is provided with an orifice 55 of small cross section intended to catch the drop that is formed at the end of the delivery of the product through orifice 52. We have designated by reference numeral 53 the chamber formed between said end wall 69 and guide 54.

10 Said hollow distributing member 51 is integral with a piston 56 adapted to be displaced by the action of compressed air fed through pipe 21, said piston 56 moving in the cylindrical bore 57 of a hollow frame 58. Advantageously, as shown, hollow frame 58 comprises an extension 59 to permit a good centering of nozzle 25. An orifice 60 is provided in frame 58-59 for the passage of the fluid product therethrough.

15 Piston 58 is subjected to the action of a return spring 61.

20 Packing rings 62 to 66 inclusive are provided to ensure fluid-tightness.

25 Guide 54 is integral with a flange 67 centered in hollow frame 58 in such manner that when said frame is fitted in nozzle 25, the whole can be secured in position by a locking ring 68.

30 This device, in combination with means for controlling valves 10 and 51, works as follows:

35 For ejection of the product (FIG. 2) no compressed air is fed through pipe 21 and piston 56 is held in its upper position by its spring 61 so that distributing valve 51 leaves the nozzle freely open at 52. The fluid product fed through pipe 26 therefore escapes through orifice 52.

40 In order to close nozzle 25 when the proper amount of product has thus been delivered (FIG. 3), compressed air is admitted through pipe conduit 21. This compressed air moves piston 56 against the action of spring 61 so that said piston closes orifice 52.

45 At the same time, a suction is produced in chamber 53 which suction holds or catches the drops of the product through the orifice of small cross section 55. Of course, the cross section of this orifice is determined in every particular case in accordance with the viscosity of the product to be delivered. Advantageously this cross section is adjustable.

50 The product which has been sucked into chamber 53 is evacuated therefrom at the end of the next upward movement of piston 56.

55 This device has, in particular, the following advantages: It permits of using delivery outlets of relatively large cross section while catching the drops so that the device can be used with all kinds of products, even of pasty consistency or containing lumps of hard material.

60 Furthermore, it permits of obtaining a very good closing of the delivery nozzle.

65 In this embodiment of our invention the delivery nozzle is mechanically operated, but it should be well understood that the invention would apply in the case of other nozzles and in particular of resilient diaphragm nozzles.

70 In a general manner, while we have, in the above description disclosed what we deem to be a practical and efficient embodiment of the present invention, it should be well understood that we do not wish to be limited thereto as there might be changes made in the arrangement, disposition and form of the parts without departing from the principle of the present invention as comprehended within the scope of the appended claims.

What we claim is:

1. A device for feeding a fluid product which comprises in combination,
a nozzle having a delivery orifice for the outflow of
said fluid product,
a hollow valve slidable in said delivery orifice for closing
it, said hollow valve including, at its outer end
thereof a wall provided with a hole,
and a fixed guide in said hollow valve adapted to
cooperate in a fluid-tight manner with said valve to
exert a suction through said hole on the drop of
said product formed at the end of the delivery there-
of on the outer side of said end wall.
2. A device for feeding a fluid product which com-
prises in combination,
a nozzle having a delivery orifice for the outflow of
said fluid product,
a hollow valve slidable in said delivery orifice for

5

closing it, said hollow valve including, at its outer end thereof a wall provided with a hole,
and means disposed in said hollow valve adapted to
co-operate with said hollow valve during closing slid-
ing of said hollow valve whereby said closing slid-
ing of said hollow valve generates a suction inside
said hollow valve.
